UNITED STATES PATENT OFFICE.

JOHNATHAN R. FREEZE, OF MIDDLETOWN, OHIO, ASSIGNOR TO THE AMERICAN ROLLING MILL COMPANY, OF NEWARK, NEW JERSEY.

METALLIC CRATE.

1,225,025.

Specification of Letters Patent. Patented May 8, 1917.

Application filed November 8, 1916. Serial No. 130,265.

To all whom it may concern:

Be it known that I, JOHNATHAN R. FREEZE, a citizen of the United States, residing at Middletown, Butler county, Ohio, have invented certain new and useful Improvements in Metallic Crates, of which the following is a specification.

While my improved metallic crate will lend itself to employment with a variety of articles to be crated, it has been devised with special regard to the crating of nestable sheet metal culverts which are somewhat typical of a class of articles presenting difficulties in being securely and otherwise satisfactorily packed to insure convenience of handling and against injury in shipment, especially shipment by sea.

My invention will be readily understood from the following description taken in connection with the accompanying drawing in which:—

Figure 1 is an end view of one of the sections of a nestable sheet-metal culvert of known form:

Fig. 2 a side elevation of the same:

Fig. 3 a side elevation of one of the cover-strips employed in uniting the longitudinal edges of the sections:

Fig. 4 a side elevation of my improved crate shown as containing a lot of the culvert sections: and

Fig. 5 a perspective view of the crate, some of the members being partially broken away to expose otherwise hidden construction.

A diversity of scales is employed in the drawing.

In the drawing:—

1, indicates a section of a nestable sheet-metal culvert, the section being a short half-tube:

2, one of the cover-strips employed in uniting the longitudinal edges of the culvert-sections:

3, a pair of angle-irons bent from sheet-metal:

4, a similar pair of angles resting upon the horizontal flanges of the first angles, the vertical flanges of the four angles projecting upwardly, and the four angles forming a sheet-metal bottom-frame:

5 and 6, similar angles forming a top-frame:

7, vertical angles disposed as columns with their ends engaging within the horizontal

flanges of the angles at the top and bottom of the crate:

8, the longitudinal edges of the angular columns, these edges being formed as tubes rolled from the edges of the angles:

9, bolts extending through the tubes of the columns and through the horizontal flanges of the angles forming the top-frame and the bottom-frame:

10, nuts on these bolts, to permit of the parts of the crate being firmly secured to each other when assembled:

11, wall-members disposed against the inner surfaces of opposite columns and provided with horizontal flanges engaging the upper surfaces of the inner flanges of angles 3:

12, a floor-sheet resting on the inner flanges of the wall-members:

13, a lot of the culvert sections packed in the improved crate: and 14 the horizontal flanges of the wall-members, these flanges projecting inwardly and resting on the inwardly projecting flanges of the bottom-frame, the floor-sheet 12 resting on these horizontal flanges 14.

Looking at Fig. 4 it will be apprehended that, as the culvert-sections are nested with their concavities downward, there will be a rather large space or chamber at the foot of the pile of sections. Floor-sheet 12 forms the floor for this chamber and wall-members 11 close the ends of the chamber. Within the chamber there may be placed the lot of cover-strips, bolts, etc., to be employed in connection with the sections. If there be no desire to provide a closed special chamber within the crate then the floor-sheet and the wall-members may be omitted.

Assuming that the crate is to be employed for culvert-sections and their uniting devices, the packing procedure may be as follows:—

The parts of the bottom-frame, the columns, and the bolts having been assembled, the wall-members 11 are placed; the floor-sheet is placed; the cover strips, etc., are disposed on the floor-sheet; the culvert-sections are piled within the columnar crate; the top angles are assembled over the columns and bolts; and the nuts are applied to the bolts and tightened and, if desired, the bolts are riveted over the nuts. The crate guards its contents in highly satisfactory manner and the package is capable of

withstanding extremely rough handling in shipping.

In view of the fact that the improved crate is liable to be in use with any of its 5 faces uppermost, it is to be understood that such terms as top, bottom, vertical, horizontal, etc., are to be considered in their relative sense only.

I claim:—

- 10 1. A crate comprising, a pair of frames adapted to form the ends of the crate, sheet-metal columns connecting the corners of one frame with the corners of the other frame, tubes formed by the longitudinal 15 edges of the columns, and bolts extending through the frames and tubes, combined substantially as set forth.
- 20 2. A crate comprising, a pair of angle-irons provided with inwardly extending flanges perforated at their ends and forming the side members of an end frame of the crate, angle-irons independent of the first-mentioned angle-irons provided with inwardly extending flanges with their ends 25 perforated in correspondence with the perforations in the first-mentioned angle-irons and forming separable end-members of the frame, the ends of the horizontal flanges of one pair of members overlapping the ends 30 of the horizontal flanges of the other pair of members, a second end frame similarly

formed of four angle irons provided with inwardly projecting flanges perforated and overlapping at their ends, columns extending from frame to frame at the corners of 35 the frames, and bolts extending from frame to frame through said perforations therein and serving to clamp together the overlapping ends of the horizontal flanges of the frame-members and to clamp the opposite 40 frames against the ends of the columns, combined substantially as set forth.

3. A crate comprising, a pair of frames formed of angle-iron, columns and bolts serving to space apart and connect the two 45 frames at their corners, wall-members engaging the columns and one of the frames and provided with inwardly projecting flanges, and a floor-plate disposed within the frame engaged by the wall-members and 50 resting on the flanges of the wall members, combined substantially as set forth.

4. A crate comprising, a sheet-metal column-member angular in cross-section, tubes formed in the longitudinal edges of 55 the column, and bolts extending through the tubes, combined substantially as set forth.

JOHNATHAN R. FREEZE.
